LOCKER ROOM BENCH OR THE LIKE

Richard G. Wagner, Muskegon Heights, Mich., assignor to Brunswick Corporation, Chicago, Ill., a corporation of Delaware

Filed Oct. 4, 1962, Ser. No. 71,989

Term of patent 14 years

(Cl. D15—11)

FIG. 1 is a top plan view of a locker room bench or the like showing my new design;

FIG. 2 is a front elevational view thereof;

FIG. 3 is a rear elevational view thereof;

FIG. 4 is an end elevational view thereof; and

FIG. 5 is an enlarged fragmentary sectional view taken at about the line 5—5 of FIG. 2.

The dominant features of the design are shown in full lines in the drawing.

The end of the bench opposite that shown is substantially identical with that shown.

I claim:
The ornamental design for a locker room bench or the like, substantially as shown and described.
